COMBINATION HAIR BRUSH AND COMB

Alexander H. Gore, Chicago, Ill.

Application January 13, 1958, Serial No. 49,229

Term of patent 14 years

(Cl. D86—8)

Fig. 1 is a side elevational view of the combination hair brush and comb, showing my new design.

Fig. 2 is a bottom plan view of the combination hair brush and comb shown in Figure 1.

Fig. 3 is a cross-sectional view taken along the line 3—3 of Figure 1.

I claim:

The ornamental design for a combination hair brush and comb, substantially as shown.
